UNITED STATES PATENT OFFICE

2,609,225

SLAB HANDLING DEVICE

Jean D. Mollendorf, Park Ridge, Ill., assignor to
 Illinois Prestcrete Co., Chicago, Ill., a corpora-
 tion of Illinois

Application September 27, 1947, Serial No. 776,433

2 Claims. (Cl. 294—67)

1

The present invention relates to a concrete slab assembly and more particularly to a handling device used in transporting an assembled unit comprising blocks or slabs of concrete or the like arranged end to end and drawn and held together by rods or the like.

It is an object of the invention to provide a simple handling device for such assemblies which can be quickly attached and detached from the assembly so as to expedite as much as possible the handling and transporting of the slab assemblies. The handling device itself is intended to be used over and over again and, therefore, is often required to be shipped between distant points while being returned from the final destination of one slab assembly to the source of another assembly to which the device is to be attached. These operations are facilitated by the small size and light weight of the present device.

The foregoing all constitute advantages of the present invention and other advantages and objects will become apparent from the description which follows and the drawings, in which

Fig. 1 is a side elevational view of a complete slab assembly shown with the handling device in place, ready for lifting the assembly;

Fig. 2 is an end elevational view of the assembly shown in Fig. 1 with the overhead carrying cable removed;

Fig. 3 is a vertical, longitudinal, sectional view taken through one end of the assembly illustrated in Fig. 1, with a portion of the view shown in elevation;

Fig. 4 is a front elevational view of the lifting arm illustrated in the prior figures; and

Fig. 5 is a side elevational view of the lifting arm illustrated in Fig. 4.

For purposes of illustration a single embodiment only of the present invention is disclosed in the drawings and will be described hereinafter. It is recognized, however, that many modifications can be made in the specific embodiment disclosed without departing from the intended scope of the invention.

Referring now to the drawings the invention is illustrated in conjunction with a slab assembly comprising a plurality of blocks 10 arranged in end to end relationship to form an elongated beam-like structure. As shown the blocks may be made of concrete, clay tile or some other such suitable material though the specific material is not important to the present invention.

As best shown in Figs. 2 and 3 each of the blocks 10 is hollow and specifically is provided with a cylindrical longitudinal opening 11 passing

2

therethrough. Adjacent to the lower edge of the blocks 10 on each side thereof is a longitudinally disposed slot or groove 12 (see Figs. 2 and 3) each of which, when the blocks are arranged end to end as shown in Fig. 1, extends throughout the entire length of the assembly. A metal rod 13 threaded at its opposite ends as at 14 is adapted to be disposed in the longitudinal extending groove 12 disposed on each side of the assembly. An end plate 14 is provided for each end of the assembly and is apertured to receive one end of each of the rods 13. Thus as shown in Fig. 1 the rods 13 project through the plates 14 and the blocks 10 are drawn together preferably under an initial compression by means of nuts 15 threaded onto the ends of the rods 13. Suitable washers 16 may be inserted between the nuts 15 and the plates 14.

As best shown in Figs. 2 and 3 the end plates 20 14 may be rectangular in shape and when mounted onto the assembled blocks 10 are disposed adjacent the lower edge of the assembly with a portion of the plates spanning the cylindrical opening 11 passing through the blocks 10.

25 A lifting arm or handle hook 17 is provided with a lower offset portion 18 which as shown in Fig. 3 is adapted to engage the inner face 19 of one end plate 14. The upper portion of the arm 17 is adapted to rest against the end of the end block 10 in the assembly. The plate 14 is apertured at 20 to receive a pin 21 in the arm 17. The arm 17 is apertured adjacent its upper end as at 22 to receive a hook 23 mounted on the end of a cable 24 used in lifting the assembly.

30 As shown in Fig. 1 a lifting arm 17 is required for both ends of the assembly and initially each of these arms is inserted in place with the lower end 18 of the arm first inserted in the hollow tile above the plate 14 and is then brought against the inner face of the plate 14 with the lug or pin 21 inserted in the aperture 20. The hooks 23 are then inserted in their respective apertures 22 and the assembly is ready to be lifted. The cables 24 are attached at their free ends to a ring 25 and during the lifting operation a suitable crane or lifting hoist (not shown) with hooks diagrammatically illustrated at 26 grasps the ring 25 and effects the lifting of the assembly.

It is to be noted that the lifting arms 17 project above the upper edge of the blocks 10. During the lifting operation the force on each of the lifting arms 17 urges the lower end of the arm 18 outwardly against the inner face 19 of the plate 14 and at the same time forces the upper portion 55 of the arm 17 against the end of the end block

10, thereby locking the lifting arm 17 to the end of the assembly. The lug or pin 21 disposed in the aperture 20 serves to prevent relative vertical movement between the lifting arm 17 and the plate 14 so as to permit lifting of the assembly.

When the slab structure is disposed at its final destination the hooks 23 are removed from their corresponding apertures 22 in the lifting arms 17 and each of the arms is very quickly and simply removed from the assembly by merely removing the upper end of the arm away from the end of the block assembly so as to permit removal of the pin 21 from the aperture 20 in plate 14 and then the lifting arm is merely withdrawn.

Thus a very simple device is provided for use in handling building structures of the type described and the lifting arms 17 together with the cables 24 can be returned to the source for use in connection for transporting other like assemblies.

It is to be noted that the present invention permits handling of the assembled slab structures without requiring the use of handling steel members across the top of the assembled structure. In other words, in conventional assembled structures steel rods are used along the upper region of the structure, these rods placing the top cord of the structure in compression so that upon lifting of the assembly the structure will hold together. The present invention completely eliminates the necessity for these additional steel rods.

I claim:

1. For use in lifting an assembly of blocks arranged end to end with an opening provided in the ends of the assembly, said blocks being held together by longitudinal means, the combination of a plate removably secured to one end of and adjacent to the lower region of the assembly and

having an inner face spanning said opening, an upstanding lifting arm having a lower portion adapted to fit into the opening and engage the inner face of the plate and an upper portion adapted to engage the end of the block assembly, the plate having an aperture therein, and a lug extending outwardly from the face of the arm that engages the face of the plate, the lug being adapted to enter the aperture.

2. For use in lifting an assembly of blocks arranged end to end and held together by longitudinally disposed rods that project beyond the opposite ends of the assembly, the combination of a plate adapted to extend crosswise across one end face of the assembly and being apertured to fit over the ends of the rods, means fastening the plate onto the rods, the end blocks having each exposed end face open in its central region, the plate being adapted to span the opening and having an inner accessible face, and an upstanding arm having lower and upper offset parallel portions, the lower portion being adapted to engage the inner face of the plate, a lug projecting outwardly from the lower offset portion on the side thereof that engages the plate, the plate having an aperture therein to receive the lug and the upper portion of the plate being adapted to engage the end face of the block.

JEAN D. MOLLENDORF.
